US0D1039780S

(12) **United States Design Patent** (10) **Patent No.:** **US D1,039,780 S**
(45) **Date of Patent:** **** Aug. 20, 2024**

(54) **SPONGES**

(71) Applicant: **The Procter & Gamble Company**,
Cincinnati, OH (US)

(72) Inventor: **Matthew Joshua Brewer**, Deerfield
Township, OH (US)

(73) Assignee: **The Procter & Gamble Company**,
Cincinnati, OH (US)

(**) Term: **15 Years**

(21) Appl. No.: **29/837,568**

(22) Filed: **May 6, 2022**

Related U.S. Application Data

(60) Division of application No. 29/757,332, filed on Nov.
5, 2020, now Pat. No. Des. 956,377, which is a
continuation of application No. 29/654,559, filed on
Jun. 26, 2018, now abandoned.

CLAIM

The ornamental design for sponges, or the like, as shown and
described above.

DESCRIPTION

FIG. 1 is a perspective view of a first embodiment of
sponges;

FIG. 2 is a front view of the embodiment of sponges shown
in FIG. 1;

FIG. 3 is a perspective view of a second embodiment of
sponges;

FIG. 4 is a front view of the embodiment of sponges shown
in FIG. 3; and,

FIG. 5 is a back view of the embodiment of sponges shown
in FIG. 3.

1 Claim, 5 Drawing Sheets
